UNITED STATES PATENT OFFICE.

JOE V. MEIGS, OF LOWELL, MASSACHUSETTS.

IMPROVEMENT IN BRACKETS FOR SHELVING.

Specification forming part of Letters Patent No. **139,408**, dated May 27, 1873; application filed April 1, 1873.

To all whom it may concern:

Be it known that I, JOE V. MEIGS, of Lowell, Massachusetts, have invented certain Improvements in Brackets for Shelving, of which the following is a specification:

The objects of my invention are so to construct brackets for the support of shelving that they may readily be applied to or removed from walls or other supports, to render the shelves adjustable, and to detach the movable part of the bracket from its fixed portion without detaching the latter from the wall; to which ends my improvement consists in combining a fixed bracket provided with guides and a detent-rack with a movable bracket carrying a pawl, which takes into the rack to hold the bracket in any desired position.

In the accompanying drawings, Figure 1 shows a view in perspective of my improved bracket; Fig. 2, a similar view, showing a portion of a shelf; and Fig. 3, a similar view of the adjustable portion of the bracket.

Guide-strips A are secured at suitable intervals to a wall or post by screws a, or other proper fastenings, and provided with a detent-rack, b. Movable brackets C, which may be of the form shown, or varied to suit the taste of the architect, are provided at their upper

ends with jaws c, which embrace guide-flanges d on the strips A. The lower leg of the bracket is provided with a pawl, e, which abuts against the notches of the detent-rack, and holds the movable bracket securely. Notches f are cut in the guide-flanges at suitable intervals, and of such size and shape as readily to permit of the insertion or removal of the jaws of the bracket without disturbing the fastenings of the guide-strip.

The bracket it will be observed clasps this strip at one point only, and plays freely upon it, so that the bracket may readily be moved up or down, and is held by the pawl in any desired position. Shelves may be secured to the bracket in any well-known way.

I claim—

The combination of a bracket-strip having notches, guides, and a detent-rack, and a movable bracket having a pawl and clasping-jaws, these members being constructed and operating in combination, substantially as set forth.

In testimony whereof I have hereunto subscribed my name.

JOE V. MEIGS.
